UNITED STATES PATENT OFFICE

164,822

SHOWER HEAD

Irving H. Russell, Oak Park, Ill., assignor to
Sloan Valve Company, Chicago, Ill., a corpora-
tion of Illinois

Application July 19, 1950, Serial No. 11,268

Term of patent 14 years

(Cl. D91—3)

To all whom it may concern:

Be it known that I, Irving H. Russell, a citizen of the United States, residing at Oak Park, in the county of Cook and State of Illinois, have invented a new, original, and ornamental Design for a Shower Head, of which the following is a specification, reference being had to the accompanying drawings, forming part thereof:

Fig. 1 is a side view of the shower head embodying my new design;

Fig. 2 is an end view of the same; and

Fig. 3 is a fragmentary side view taken along the line 3—3 of Fig. 1.

The dominant features of my design reside in the portions shown in full lines.

I claim:

The ornamental design for a shower head, substantially as shown and described.

IRVING H. RUSSELL.
